UNITED STATES PATENT OFFICE

BENJAMIN LEWIS PADGETT, OF WASHINGTON, DISTRICT OF COLUMBIA

GRAPHIC REPRESENTATION

Application filed July 26, 1929. Serial No. 381,334.

This invention relates to graphic representation and has particular relation to the production of curves.

In the production of graphics by coordinates, the use of curves is common. These curves are usually drawn on cross lined paper. When additional or changed data make changes in the representations necessary, the operator must draw in the additional line or 10 lines or erase the incorrect lines and replace them with new lines. With the use of ink, changes are difficult because of the resistance of the ink to removal and the liability of tearing the sheet upon which the graphic representation is being placed.

It is to obviate the above difficulties in the production of graphic representation that my present invention is directed and

The primary object of my invention is the 20 production of an improved and rapid means of graphic representation which may be quickly and easily changed when such change is desired.

Another object of this invention is the provision of a device for the representation of curves in which a flexible member is used to represent the curve.

Another object of this invention is the provision of a graphic representation device having 30 a board, rows of holes in the board, pins to go into the holes in the board, and a flexible member to connect the pins together.

Still another object of the invention is the provision of a graphic representation device having rows of cross lines and lines of holes corresponding to the lines with pins for the holes and a flexible member to connect the pins together.

A still further object is the provision of 40 such a graphic representation device having a black board and a white flexible strip of cardboard for indicating curves on the board.

Another and still further object of the invention is the process of laying off a series 45 of points on a board of color characteristics to have little effect upon the active surface of a photographic paper, then connecting the points with a flexible strip of color characteristics to effect the active surface of a photo-

tographic paper and finally the making of a direct photograph of the board.

Referring to the drawing wherein I have illustrated an embodiment of my invention; Figure 1 is a perspective view illustrating 55 the construction of the invention.

Figure 2 is a view illustrating the photographic reproduction of the board as used.

Figure 3 is a detail cross sectional view on the line 3-3 of Figure 1.

Figure 4 is a detail view of a portion of one curve indicating strip.

Figure 5 is a view similar to Figure 4, but of another strip.

In the drawings, the same or similar parts are designated by the same reference character.

In Figure 1, I have shown a board 10 having an ordinate line 11 and an abscissa line 12.

In carrying out my invention, I provide a flexible member to indicate the curve showing the graphic representation. This I have exemplified in the flexible bristol board strip 13 shown in Figures 1 and 3.

To hold the strip 13 in place, I have provided means for coaction between the board 10 and strip 13. The means in the embodiment illustrated for holding the strip in place, comprises the holes 14 and the pins 15. 80 These holes 14 are preferably located on cross lines on the board shown at 16 and 17, the lines 16 being horizontal along which abscissæ are measured and the lines 17 extending at right angles thereto and along 85 which ordinates are measured.

The board 10 is preferably red or black or of some color which will have little or no effect upon the sensitive coating of a photographic paper. The flexible curve indicating 90 member 13 preferably has color characteristics different from those of the board 10 and when the latter is black or red or of some similar color characteristics, the curve indicating member may be white.

Indicia of the ordinates and abscissæ may be marked adjacent the origin lines to facilitate the laying off of values for the graphic representation. The data for the ordinates and abscissæ being before the operator, the 100

points corresponding thereto are found and indicated in some way as by marking them on the board or by placing the pins in appropriate holes.

5 In order to secure the flexible strip 13 in place, pins 15 are placed in appropriate holes in the board in a manner to contact with the flexible strip 13 to hold it securely in the desired position. The pins 15 are preferably 10 made of the color characteristics of the board so that when the board is photographed, the pins will not be apparent.

When the points to be located are all placed in their proper places and the flexible member has been applied, the next step in the 15 method, is the photographing of the whole face of the board.

An advantage of the invention is that the board with its curve or curves may be photographed at any time and the material used again. As many photographic copies may be made as are necessary. The curve may be extended by using a longer flexible member or by normally placing a paper or other mask, 25 of the color characteristics of the board, over the end of the plotted curve. This I have indicated by the dotted lines on the board at 18.

As more points are plotted, the mask is 30 moved to expose more of the curve. By using such a mask having the color characteristics of the board, the curve appears in photographs as ending at the edge of the mask.

It may be found to be desirable to have 35 more than one curve illustrated. This may be done in any suitable manner as, when the strips are used, by cutting away half of each strip as shown in Figures 4 and 5. The strip 13 may be cut away on its top as at 13^a and 40 the curve indicating strip 19, on its bottom as at 19^a. The view from above, either from the eye or in a photograph does not show the cut away portion prominently and with proper light, it would not show at all.

45 While I have illustrated and described in detail an embodiment of my invention, I desire to have it understood that I do not limit myself to the exact showing and that modifications and changes as to the construction, 50 type and color of details may be made without departing from the spirit of my invention and within the scope of the appended claims.

Having described my invention, what I claim and desire to secure by Letters Patent 55 is:—

1. A graphic representation device comprising a board, a thin resilient member, means for holding the thin resilient member on the board to give a graphic representation.

60 2. A graphic representation device comprising a board, holes in the board, a thin resilient member, means, including pins to insert in the holes for holding the thin resilient member on the board to give a graphic 65 representation.

3. A graphic representation device comprising a black board, holes in the board, a light colored, thin, resilient member, means including pins to insert in the holes for holding the thin resilient member on the board 70 to give a graphic representation.

4. A graphic representation device comprising a board, holes in the board, a narrow, thin strip of resilient material, means including pins to insert in the holes for holding the thin resilient strip edgewise on the board to give a graphic representation. 75

5. A graphic representation device comprising a board, the board having coordinate lines thereon, a thin resilient member, 80 means for holding the thin resilient member on the board to give a graphic representation.

6. A process for producing graphic representation comprising the marking off of points on a board at given distance therefrom 85 relative to an origin, the connection of these points with a resilient strip member and the photographing of the board with the strip thereon.

7. A process for producing graphic representations comprising the placing of pins at points on a board, the light from which has little effect upon a photographic paper, the securing of a resilient strip, of a color to effect a photographic paper, to the pins, and the 95 making of a photograph of the board and strip, directly onto a photographic paper.

In testimony whereof, I hereunto affix my signature.

BENJAMIN LEWIS PADGETT.
